UNITED STATES PATENT OFFICE.

SAM F. KLOHS, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CARLINE STRUCTURE.

1,136,964.

Specification of Letters Patent. Patented Apr. 27, 1915.

Application filed January 5, 1912. Serial No. 669,670.

To all whom it may concern:

Be it known that I, SAM F. KLOHS, a citizen of the United States, residing in Chicago, in the county of Cook and State of Illinois, 5 have invented a new and useful Improvement in Carline Structure, of which the following is a specification.

The object of this invention is to provide a new and improved carline structure, for 10 freight cars, that is especially adapted to resist the lateral, longitudinal and diagonal strains of the car roof, and a more specific object is to provide a carline which is constructed from any of the well known structural shapes of metallic beams and one that comprises a main body-member extending 15 from side plate to side plate and provided near each end with one or more diagonally extending brace members rigidly secured 20 and extending at an angle, to the main member, said brace members being preferably formed with inverted U-shaped hangers at their outer ends, whereby a rigid carline 25 is formed and one that is light in proportion to its strength.

My invention furthermore consists in improvements in the parts and devices and in the combinations of the parts and devices herein shown, described or claimed.

20 In the drawings forming a part of this specification Figure 1 is a plan view of a carline embodying my improvements, showing, in addition to the carline, portions of the side plates and the ridge pole. Fig. 2 is a 25 transverse vertical section showing the structure disclosed in Fig. 1 as applied to an inside metal car roof. Fig. 3 is a detailed transverse section, upon an enlarged scale, taken on the line 3—3 of Fig. 1. Fig. 4 is a 30 view similar to Fig. 1 showing a carline which consists of a channel iron in an inverted position. Fig. 5 is a transverse vertical section of approximately half the width of the car, showing the structure disclosed in Fig. 4 as applied to an outside car 35 roof. Fig. 6 is a detailed section, upon an enlarged scale, of the structure shown in Fig. 5, taken on the line 6—6. Fig. 7 is a 40 view similar to Fig. 1 showing another form of carline, made from an angle iron. Fig. 45 50 Fig. 8 is a transverse section of the structure shown in Fig. 7, upon an enlarged scale, showing the same carline as applied to an inside metal car roof. Fig. 9 is a transverse 55 section, upon an enlarged scale, taken on the

line 9—9 of Fig. 7. Fig. 10 is a view similar to Fig. 7 showing the angle iron, composing the carline, inverted. Fig. 11 is a detailed transverse section showing the structure disclosed in Fig. 10 as applied to an outside car 60 roof. Fig. 12 is a detailed section, upon an enlarged scale, of the structure shown in Fig. 11 taken on the line 12—12. Fig. 13 shows another way of applying the structure shown in Fig. 7 to an outside car roof. 65

In the drawings, and referring more particularly to Figs. 1, 2 and 3, 20 denotes a carline beam which may be constituted of any one of the well known structural shapes of metallic rolled beams, the form shown 70 in said figures being that of a channel having the flanges thereof turned downwardly. The beam 20 which extends between the side plates 21, 21, is composed of members which are substantially at right angles to each other throughout the length of the beam, said members comprising the web 22 and flanges 23, it being obvious that the flanges 23 extend in vertical planes. At each end 75 of the beam 20 the web is extended beyond the ends of the flanges and the extended portion 24 is bent downwardly and secured to the side plates by means of bolts 25. Firmly secured to each beam 20 at a point removed from the bent end portions 24, are brace 80 members 26, preferably made of an angle iron having the vertical leg on each side of the beam 20 bent inwardly and secured to each of the flanges 23 of the channel as shown more clearly in Fig. 3. Each brace 85 member 26 has diagonally extending members 27, each member 27 having at its outer end means for securing the same to the side plate 21, said securing means being preferably in the form of an inverted hanger 90 formed by making an inverted U, 28, in the horizontal member 29 and bending the vertical member 30 as at 31 whereby the latter may be secured by bolts or other fastening means to the side plate. As shown in Fig. 2 the main member 20 of the carline is deflected downwardly on each side of the center thereof and supports the purlin 32 on 95 which is mounted the metallic roofing 33, and exterior thereof the roof boards 34. 100

In Fig. 4 the structure employed is a channel 120 similar to that shown in Figs. 1, 2 and 3, only in Fig. 4 the channel is shown with flanges extending upwardly 110 from the web instead of downwardly there.

from. In the structure shown in Fig. 4 the brace member 126 is similar to that shown in the earlier figures and is secured to the member 120 beneath the same instead of on top, as shown in Fig. 5.

In Figs. 5 and 6, where the channel is employed with an outside roof, a filler or nailing block 35, which is somewhat wedge shaped in cross section, is secured between 10 the flanges of the beam, as by means of bolts 36, and it will be obvious that the roof boards 37 which extend longitudinally of the car may be nailed to this wedge shaped filler block.

15 In Fig. 7 I have shown another modification of the carline employing an angle iron extending across the car, said carline comprising a main member 220 having a vertical leg 223 which at each end has a portion bent 20 at right angles to the main portion and which is secured to the side plates 21 as at 224. In the structure shown in Fig. 7 the other member 222 of the main portion 220 of the carline is formed at each end into an 25 inverted hanger 225 adapted to be seated over the side plate 21. In this form the bracing member comprises only one diagonally extending member 227 which is preferably in the form of an angle iron having 30 the vertical leg thereof secured to the vertical leg 223 of the member 220 as shown more clearly in Fig. 9. The member 227 is also 35 preferably formed with an inverted hanger at its outer end as in the structures previously described.

In Figs. 10, 11 and 12 the main member of the carline consists of the same form of structural beam as shown in Figs. 7, 8 and 9, the only difference being that the angle 320 40 is shown with the horizontal flange in the upper position. In this structure also the bracing member 327 is inverted. In employing the carline 320 in an outside roof structure, the nailing or filler block 325 is secured 45 to the legs of the angle as by means of bolts 336.

In Fig. 13 is shown the form of carline disclosed in Fig. 7, the same being employed in connection with an outside roof and having a nailing strip 435 secured to the upper flange 422 thereof.

I have shown my carline as having the main body member made from commercially rolled channel and angle irons but it will be

obvious that other forms of structural shapes, 55 such as T's, I's and Z's, may be used without departing from the spirit of the invention; and said member may be of pressed steel, or other suitable material, instead of commercially rolled stock. And other variations 60 may be made in the carline, within the scope of the several claims here following.

I claim:

1. In a carline structure, the combination 65 of a metallic beam composed of a horizontal web and vertical flanges at the sides thereof, the said web being bent to extend vertically in engagement with the face of the side plate; and diagonal brace members each composed of a horizontal flange and a vertical flange, the horizontal flange having its ends bent into U-form to engage the inner side, the top and the outer side of the side plate, and the vertical flange being bent parallel with the vertical flanges of the beam 75 and secured to said vertical flanges, substantially as set forth.

2. In a carline structure, the combination 80 of a metallic beam composed of a horizontal web and vertical flanges at the sides thereof, the said web being bent to extend vertically in engagement with the face of the side plate; and diagonal brace members each composed of a horizontal flange and a vertical flange, the horizontal flange being extended across and secured to the said web of the beam and having its ends bent into U-form to engage the inner side, the top and 85 the outer side of the side plate, and the vertical flange being bent parallel with the vertical flanges of the beam and secured to said vertical flanges, substantially as set forth.

3. In a carline structure, the combination 90 with the side plates, of a metallic beam extending across the car and formed with a horizontal web and a vertical web, and diagonal bracing members formed with a horizontal web and a vertical web, the vertical webs of the bracing members being bent parallel with and secured to the vertical web 95 of the said beam and the horizontal webs of the bracing members being bent to inclose the side plates, substantially as set forth.

SAM F. KLOHS.
